(57) **CLAIM**

The ornamental design for the music instrument tuner, as shown and described.

DESCRIPTION

FIG. 1 is a bottom perspective view of the music instrument tuner;

FIG. 2 is a top perspective view of the music instrument tuner of FIG. 1;

FIG. 3 is a top view of the music instrument tuner of FIG. 1;

FIG. 4 is a bottom view of the music instrument tuner of FIG. 1;

FIG. 5 is a rear end view of the music instrument tuner of FIG. 1;

FIG. 6 is a front end view of the music instrument tuner of FIG. 1;

FIG. 7 is a left side view of the music instrument tuner of FIG. 1, relative to the view of FIG. 3; and,

FIG. 8 is a right side view of the music instrument tuner of FIG. 1, relative to the view of FIG. 3.

The broken lines in FIGS. 1-8 represent the portions of the music instrument tuner, which form no part of the claimed design.
